UNITED STATES PATENT OFFICE.

ELIZABETH F. VILKOMERSON, OF NEW YORK, N. Y.

HOLDER FOR FOUNTAIN-PENS.

1,166,282.

Specification of Letters Patent.

Patented Dec. 28, 1915.

Application filed June 10, 1915. Serial No. 33,365.

To all whom it may concern:

Be it known that I, ELIZABETH F. VILKOMERSON, a citizen of the United States, residing at New York, in the county of 5 New York and State of New York, have invented certain new and useful Improvements in Holders for Fountain-Pens, of which the following is a specification.

This invention relates to devices for carrying fountain pens and has for its object 10 the provision of a device of that character which may be attached to an outer garment, such as a shirt waist, or bodice, or vest, or coat, and at a convenient point 15 where the pen may be easily and quickly secured or removed, and which will carry the pen in a vertical position and hold it rigidly in such a position so that it can not tilt or swing laterally, and at the same 20 time permit of its being easily and quickly engaged or disengaged from the holder.

Another object is to provide a device of this character which will be of slighty appearance and durable and which can be economically manufactured.

With these objects and advantages in view the invention consists in the novel details of construction and arrangements of parts hereinafter more fully described and 30 claimed, and illustrated in the accompanying drawings, in which:

Figure 1 is a side elevation showing my device attached to a fountain pen, Fig. 2 is a front view in elevation of my device with 35 the pen removed, Fig. 3 is a rear view of the same, Fig. 4 is a front view in perspective of the garment engaging member of my device, and Fig. 5 is a perspective view of the pen engagaing member thereof.

40 In the drawings in which like numerals designate like parts, the numeral 1 designates the garment engaging member and is formed of a single piece of material and provided on the rear side of its top portion 45 2 with a pin 3 pivoted as at 4 and engageable in a catch 5. The downwardly extending portion 6 of the member 1 is formed integral with the top portion 2 and has a transverse slot 7 for the reception of the 50 pen engaging member.

The pen engaging member is designated

as a whole by the numeral 8 and comprises a single piece of material preferably spring metal formed as a split spring band 9. Formed integrally upon and extending upwardly from the top edge and then bent downwardly upon itself is a tongue 10 bent to form a spring hook. Square shoulders 11 extend from each side of the upper part of the tongue and are adapted to keep the 60 pen in a vertical position and against lateral movement by abutting the portion 6 of the garment engaging member 1. The tongue 10 is bent down upon itself and then inwardly and then outwardly, as shown in 65 Fig. 1, to form a bearing point 12. The band 9 is slipped over the pen 13 and held in position by its spring.

The pen is supported by engaging the tongue 10 in the slot 7 in the portion 6, and 70 is held in a vertical and firm and rigid position by the shoulders 11 of the tongue bearing against the sides of the slot 7 which being rectangular in shape and the tongue rectangular in cross-section, causes a snug 75 fit and prevents any swinging movement of the pen, while the tongue being bent outwardly and formed of spring metal renders the device simple and easy to manipulate.

I have shown in Fig. 1 the band 9 secured 80 to the cap of the pen, but it will be obvious that the band may be attached to either the cap or the barrel of the pen without departing from the principle or spirit of my invention. If attached to the barrel of the pen 85 any tendency of the barrel weighted with ink to work itself downwardly and become loose or separated from the cap would be obviated.

Having thus described my invention what 90 I claim is:

1. In a fountain pen holder having a garment engaging member, a pen engaging member comprising a band having a tongue integral therewith, said tongue being bent 95 to form a hook and provided with shoulders to engage said garment engaging member.

2. In a fountain pen holder, a pen engaging member comprising a split band having a tongue thereon, said tongue having a square shoulder on each side to form bearing portions and bent back on said band 100

to form a hook, and a bearing point on said tongue.

3. In a fountain pen holder, a pen engaging member comprising a split band, a tongue on said band bent back upon itself to form a hook, said hook being bent inward and then outward to form a bearing point adjacent its end, and shoulders formed on

each side of said tongue to form bearing surfaces.

In testimony whereof I hereto affix my signature. ¹⁰

ELIZABETH F. VILKOMERSON.

Corrections in Letters Patent No. 1,166,282.

It is hereby certified that in Letters Patent No. 1,166,282, granted December 28, 1915, upon the application of Elizabeth F. Vilkomerson, of New York, N. Y., for an improvement in "Holders for Fountain-Pens," errors appear requiring correction as follows: In heading to the drawings, line 3, for "Application filed Jan. 10, 1915," read *Application filed June 10, 1915*; page 1, line 39, for the word "engaging" read *engaging*; and that the said Letters Patent should be read with these corrections therein that the same may conform to the record of the case in the Patent Office.

Signed and sealed this 18th day of January, A. D., 1916.

[SEAL.]

J. T. NEWTON,

Acting Commissioner of Patents.
